HAND-HELD EMBOSsing GUN

Leo F. Wildgen, Bloomington, Minn., assignor to Minnesota Mining & Manufacturing Company, St. Paul, Minn.

Filed Oct. 12, 1973, Ser. No. 405,795

Term of patent 14 years

Int. Cl. D15—09

U.S. Cl. D64—10

FIG. 1

FIG. 2

FIG. 3

FIG. 4

FIG. 5

FIG. 6

FIG. 7

FIG. 1 is a perspective view of a hand-held embossing gun showing my new design;
 FIG. 2 is a top plan view thereof;
 FIG. 3 is a left side elevational view thereof;
 FIG. 4 is a right side elevational view thereof;
 FIG. 5 is a bottom side elevational view thereof;
 FIG. 6 is a front elevational view thereof; and
 FIG. 7 is a rear elevational view thereof.

I claim:
 The ornamental design for a hand-held embossing gun, substantially as shown.
